UNITED STATES PATENT OFFICE

164,522

COIN HOLDER OR THE LIKE

Wilfred E. Stageberg, Minneapolis, Minn., assignor to Brown & Bigelow, St. Paul, Minn., a corporation of Minnesota

Application May 4, 1950, Serial No. 9,711

Term of patent 14 years

(Cl. D87—3)

To all whom it may concern:

Be it known that I, Wilfred E. Stageberg, a citizen of the United States, residing in Minneapolis, county of Hennepin, and State of Minnesota, have invented a new, original, and ornamental Design for a Coin Holder or the like, for which the following is a specification, reference being had to the accompanying drawing, forming part thereof.

Figures 2 and 3 are side elevational views illustrating the coin holder in open and closed positions, respectively; and

I claim:

The ornamental design for a coin holder or the like, as shown.

WILFRED E. STAGEBERG.
